FINGER RING

James R. Howe, Lincoln, R.I.
(383 Westminster St., Providence, R.I. 02903)

Filed Nov. 13, 1967, Ser. No. 9,381

Term of patent 14 years

(Cl. D45—10)

FIG. 1

FIG. 2

FIG. 3

FIG. 4

FIG. 5

FIG. 6

FIG. 7

FIG. 1 is a perspective view of a finger ring showing my new design;

FIG. 2 is an elevational view of one end thereof;

FIG. 3 is a side elevational view of one end thereof looking from the right as seen in FIG. 2;

FIG. 4 is an elevational view of the end thereof reverse to that seen in FIG. 2;

FIG. 5 is a top plan view thereof;

FIG. 6 is a side elevational view of the other side thereof looking from the left as seen in FIG. 2; and

FIG. 7 is a bottom plan view thereof.

I claim:

The ornamental design for a finger ring, substantially as shown.
